Primary Examiner — Philip S Hyder(74) *Attorney, Agent, or Firm* — Volpe Koenig(57) **CLAIM**

The ornamental design for a screwdriver handle, as shown and described.

DESCRIPTION

FIG. 1 is a front elevational view of a screwdriver handle in accordance with my design;

FIG. 2 is a bottom plan view thereof;

FIG. 3 is a top plan thereof;

FIG. 4 is a rear elevational view thereof;

FIG. 5 is a right side elevational view thereof;

FIG. 6 is a left side elevational view thereof; and,

FIG. 7 is a perspective view thereof.

The broken lines represent portions of the screwdriver handle in which the design is embodied that form no part of the claimed design.
